UNITED STATES PATENT OFFICE.

LEE DE FOREST, OF NEW YORK, N. Y.

DESIGN FOR A LOUD SPEAKER.

Application filed October 17, 1925. Serial No. 15,164. Term of patent 14 years.

To all whom it may concern:

Be it known that I, LEE DE FOREST, a citizen of the United States, residing at New York, in the county and State of New York, have invented a new, original, and ornamental Design for Loud Speakers, of which the following is a specification, reference being had to the accompanying drawing, forming part thereof.

In the figures, Fig. 1 is a front elevational view of a loud speaker showing my new design.

Fig. 2 is a side elevational view of a loud speaker, showing further my new design.

Fig. 3 is a top plan view of a loud speaker showing more of my new design.

I claim:

The ornamental design for a loud speaker, as shown.

In testimony whereof I have hereunto set my hand on this 15th day of October A. D., 1925.

LEE DE FOREST.
